B. M. BLAKE

HYDRANT

Filed June 22, 1925

UNITED STATES PATENT OFFICE.

BERT M. BLAKE, OF LOS ANGELES, CALIFORNIA, ASSIGNOR TO EDWARD L. RICK, OF LOS ANGELES, CALIFORNIA, DOING BUSINESS UNDER THE FIRM NAME AND STYLE OF THE RICK COMPANY.

HYDRANT.

Application filed June 22, 1925. Serial No. 38,737.

This invention relates to hydrants or water plugs of the type employed, for example, in supplying water from a water main to the fire hose. 55

With the hydrants or plugs of the type at present employed for supplying water from the water main to the fire hose, it is customary upon an alarm of fire for the fire engine to pull up to the hydrant and drop 60

one end of the hose which the fireman connects with the hydrant and the fireman then opens the valve in the hydrant while the engine is laying the hose to the fire. The water is thus played upon the fire very 65

quickly, but if the fire is relatively large it is necessary to increase the water pressure over that in the main and, accordingly, the engine is returned to the hydrant and the valve in the hydrant is closed and then the 70

hose is disconnected from the hydrant and connected with the discharge of the pump on the engine. Also a short hose is connected between the intake of the pump and the hydrant. The water is then turned on 75

at the hydrant and the pump operated so as to pump the water under relatively high pressure through the fire hose.

It will be obvious from the foregoing statement that, at a critical time in the fighting of the fire, the flow of water onto the fire is discontinued while the connections with the engine are being made, and during this interval of time the fire may gain a dangerous headway so as to make it somewhat difficult to bring under control when the water is again turned on.

In an effort to avoid the turning off of the water while changing from the city pressure to the higher pressure of the fire engine, four-way valves have been designed to be used on the plug end of the hose and said valves are dropped with the hose at the plug. In these valves one of the ports is connected with the plug, another to the fire hose, and the other two to intake and outlet ports, respectively, of the pump. When the hose is first connected with the plug the water is turned on and runs from the plug to the hose line. After sufficient time has elapsed to connect up the plug with the fire engine, the four-way valve is operated to direct the water from the fire plug to the engine and to direct the water received from the engine to the fire hose. These four-way valves easily become leaky, are liable to become damaged in handling with the hose and are then very hard to operate. They are also very heavy when made large enough to pass the required amount of water without undue frictional losses. 105

An object of this invention is to avoid the foregoing difficulties.

Another object is to provide for automatic action of the valve that changes the direction of the flow of water from the main to the fire hose so that when the engine is attached and the pump started into operation the water will immediately flow from the main through the engine to the fire hose instead of directly from the main to the fire hose.

The accompanying drawings illustrate the invention:

Fig. 1 is a perspective view showing a hydrant or plug embodying the invention and connected by intake and outlet hose lines to a fire engine which is fragmentarily shown. A fragment of the fire hose is also shown leading from the hydrant.

Fig. 2 is an elevation mainly in vertical midsection of the hydrant shown in Fig. 1.

Fig. 3 is a plan view, mainly in section, from the line indicated by 3—3, Fig. 2.

There is provided a hollow standard or member forming lower and upper chambers 85 4 and 5 which may be thrown into communication through a port 6 connecting them. The term "free-operating" applied to the check valve 7 denotes that the check valve is free at all times to operate into either open or closed position and that only differences in pressure in the chambers 4, 5 are relied upon to hold the check valve in the closed and open positions so that the instant the pressure in one chamber becomes greater than that in the other, the check valve will automatically operate without any attention being given to it. The port 6 is controlled by a free-operating check valve 7 which closes toward the chamber 4 and opens toward the chamber 5. The chamber 4 is provided with an outlet port 8 controlled by a suitable valve 9 which may be of any well known construction, the stem 10 of said valve passing through the wall of the chamber 4 so that it may be manipulated.

for opening and closing the valve 9. In Fig. 2 the port 8 is closed by a cap 11 which will be removed when it is desired to connect the suction hose of the engine. Such suction 5 hose is indicated in Fig. 1 at 12 and said hose connects with the suction or intake port *a* of the pump of the fire engine, said engine being fragmentarily indicated at 13. The chamber 5 has a plurality of ports 10 14, 15. It is necessary to have at least two and two are shown, but it is to be understood that if it be desired to connect a plurality of hose lines it is necessary to have one more port in the chamber 5 than there 15 are hose lines to be run from the plug to the fire. One of the ports 14, 15 is an outlet and the other an inlet and, for purposes of description, it will be assumed that the port 14 is the outlet and the port 15 the inlet. The 20 ports 14, 15 are controlled by valves, of which only the operating stems 16 can be seen in the drawings because of the nature of the views. The base of the hydrant has a flange 17 which may be secured by bolts 25 18 to the water main *b*, indicated in broken lines in Fig. 2. The chamber 4 communicates with the main *b* through a port 25 in its lower end. The chamber 5 has its upper end closed by a chambered cap 19 and between the chamber 20 of the cap and the chamber 5 is a diaphragm 21 of rubber or other suitable flexible material, the marginal portion of the diaphragm constituting a gasket 22 to insure against leakage at the 30 joint between the cap and the member 5. Bolts 26 clamp the cap upon the gasket 22. The chamber 20 is an air space maintained by the diaphragm so that when the water pressure in the chamber 5 changes rapidly, 35 as upon sudden opening and closing of the valves, hammering of the water will not occur.

As shown in Fig. 1, the outlet 14 is connected with a fire hose line 23 and the intake 40 15 is connected by a hose 24 to the outlet *c* of the pump.

The invention operates as follows: As

soon as the fire engine reaches the fire plug a fireman drops one end of the hose, fragmentarily indicated at 23, and a fireman 50 connects said hose with the outlet port 14, as in Fig. 1, and turns on the water to said hose, and the engine is run toward the fire and proceeds to lay the hose. If the fire requires that the water pressure be increased 55 over that in the main, the engine will be returned to the fire plug and the hose 12, 24 will be connected in the manner above described and the pump will be operated. As soon as the operation of the pump causes the 60 pressure in the chamber 5 to exceed that in the chamber 4, the valve 7 will automatically close and the water will then flow from the chamber 4 to the pump and from the pump to the chamber 5 and thence through the hose 65 line 23 to the fire. It will be seen that during the operations described above, the water is flowing continuously through the hose line 23 and it will also be noted that there is no wastage of water during the transition from 70 city pressure to engine pressure. When the pump is shut down the pressure beneath the valve 7 increases and said valve automatically opens.

I claim:

A hollow standard forming lower and upper chambers and provided with a port communicating one chamber with the other, a free-operating check valve controlling said port and closing downwardly toward the 75 lower chamber, the upper chamber provided with a valved inlet adapted for connection with the outlet of a pump, the upper chamber provided with a valved outlet adapted for connection with a fire hose, the lower 80 chamber provided with a valved outlet adapted for connection with the inlet of the pump and the lower chamber provided with an inlet adapted for connection with a water main.

Signed at Los Angeles, California, this 90 13th day of June, 1925.

BERT M. BLAKE.
